UNITED STATES PATENT OFFICE.

WILLIAM G. SIMPSON, OF DETROIT, MICHIGAN.

HYDROCARBON OR GASOLENE TURBINE-MOTOR.

1,339,483.

Specification of Letters Patent. Patented May 11, 1920.

Application filed March 4, 1919. Serial No. 280,593.

To all whom it may concern:

Be it known that I, WILLIAM G. SIMPSON, a citizen of the United States, residing at 1666 Brush street, in the city of Detroit, in 5 the county of Wayne and State of Michigan, have invented a new and useful Hydrocarbon or Gasolene Turbine-Motor, of which the following is a specification.

This invention relates to new and useful 10 improvements in explosive turbines and has for an object provision of a device of this character, simple of construction and parts of which are readily replaced.

A further object is a provision of the 15 above character wherein the entire effective energy of explosion is exerted upon the vanes of the turbine.

Other objects and advantages will be obvious during the course of the following 20 discussion.

In the drawings wherein for the purpose of illustration is shown the preferred embodiment of my invention, and wherein like numerals designate like parts thereof. The 25 figure is a transverse section through my turbine.

Referring now more particularly to the drawing, the numeral 1 indicates a casing having end closures 2 and 3.

30 A shaft 4 is mounted within the casing in suitable bearings 5 and 6. Intermediate these bearings the shaft is provided with a sleeve 7, having eccentrics 8 and 9 formed thereon. The sleeve 7 is provided with a 35 keyway 10 for a purpose hereinafter to appear.

Secured to the shaft 4 is a gear 11 mounted in a bearing 12 formed in the end plate 3 of the casing is a stub shaft 13. 40 Mounted upon this stub shaft is a gear 14 meshing with the gear 11 upon shaft 4. Secured to the gear 14 is a gear 15, which 45 meshes with a gear 9 rotatably mounted upon a shaft 4. The gear 9 is provided with keys adapted to enter the keyway 10 formed in the sleeve 7.

Formed in the casing 1 is a cylinder 16 within which is mounted a piston 17 connected by a pitman 18 to the eccentric strap 50 19, which in turn receives eccentric 8. An intake chamber 20 is provided in casing 1. The communication between the intake chamber and the cylinder is closed by means of a puppet valve 21, the stem 22 of which 55 is adapted to be contacted by the eccentric 9 on the sleeve 7 at each revolution thereof.

A valve 23 governed by a dash-pot of any suitable construction closes communication between the cylinder 16 and chamber 25. This chamber 25 is provided with a reduced 60 nozzle or opening directed against vanes 27, secured to, or formed upon a fly wheel 26 secured to the shaft 4.

Secured to the gear 15 is a bevel gear 28 which meshes with a bevel pinion 20 adapted 65 to operate a timer 30 of any suitable construction.

The operation of my device is as follows:

The shaft 4 is rotated until the charge is drawn into the cylinder and compressed, 70 when it will be exploded in the usual manner. The spring of the dash pot is set at a suitable point slightly higher than the point of compression in the cylinder 16, that is to say, if the point of compression in the cylinder 16 is 70 pounds the dash-pot spring is set at 75 pounds or thereabout.

It will readily be seen that under the force of the explosion the dash-pot valve is opened and the exhausting gas impinge 80 against the vanes of the fly wheel rotates the same.

It will readily be seen that as long as the pressure within the chamber remains at more than 75 pounds the dash pot actuated 85 valve will remain open and exhaust continue. As soon however, as the pressure drops below this point, this valve closes and the cycle is again repeated. By supplying a suitable governor for the dash-pot, and 90 the timer, the operation of the turbine may be governed so that the number of explosions are entirely under control of the operator. It will of course, be understood, that some suitable means for disconnecting 95 the timer during the period at which the dash-pot valve is open must be supplied.

It is to be understood that the form of my invention herein shown and described is to be taken as the preferred embodiment of 100 the same and that various changes in the shape, size and arrangement of parts may be resorted to without departing from the spirit of the invention or the scope of the subjoined claims.

105 What I claim is,

1. In a device of the type described a casing, a shaft rotatably mounted within said casing, a sleeve rotatably mounted upon said shaft, a reducing gear train connecting said 110 shaft and said sleeve and eccentric carried by said sleeve, a cylinder formed in said

casing, a piston reciprocable therein, means connecting said piston and said eccentric whereby said piston is reciprocated when said sleeve is rotated, means for supplying a combustible charge to said cylinder, an exhaust valve for said cylinder adapted to be opened when the pressure in said cylinder exceeds the compression pressure thereof and a fly wheel secured to said shaft and extending into the path of the exhaust gases.

2. In a device of the type described a casing, a shaft rotatably mounted within said casing, a sleeve rotatably mounted upon said shaft, a reducing gear train connecting said shaft and said sleeve, a cylinder formed in

said casing, a piston reciprocable therein, means connecting said piston and said eccentric whereby said piston is reciprocated when said sleeve is rotated, means for supplying a combustible charge to said cylinder, a dash-pot controlled exhaust valve for said cylinder adapted to be opened when the pressure in said cylinder exceeds the compression pressure thereof, and a fly wheel secured to said shaft provided with vanes disposed in the path of said exhaust. 20 25

WILLIAM G. SIMPSON.
